US00D924843S

(12) **United States Design Patent** (10) Patent No.: **US D924,843 S**
(45) Date of Patent: **** Jul. 13, 2021**

(54) **AUDIO PLAYER**

(71) Applicant: **LG ELECTRONICS INC.**, Seoul (KR)
(72) Inventors: **Jun Ki Kim**, Seoul (KR); **Sungyong Park**, Seoul (KR); **Chulhee Lim**, Seoul (KR); **Chaelin Lee**, Seoul (KR)
(73) Assignee: **LG ELECTRONICS INC.**, Seoul (KR)
(**) Term: **15 Years**

(21) Appl. No.: **35/508,360**

(22) Filed: **May 21, 2019**

(80) **Hague Agreement Data**

Int. Filing Date: **May 21, 2019**
Int. Reg. No.: **DM/205149**
Int. Reg. Date: **May 21, 2019**
Int. Reg. Pub. Date: **Jan. 17, 2020**
